CLAIM

U.S. PATENT DOCUMENTS

The ornamental design for a knife edge tapering blunt cannula proximal portion, as shown and described.

DESCRIPTION

2,989,053 A	6/1961	Hamilton
3,352,531 A	11/1967	Kilm Marx
4,058,121 A	11/1977	Choksi et al.
4,106,491 A	8/1978	Guerra
4,578,063 A	3/1986	Inman et al.
4,610,374 A	9/1986	Buehler
4,710,180 A	12/1987	Johnson
4,795,446 A	1/1989	Fecht
4,834,716 A	5/1989	Ogle, II
4,904,238 A	2/1990	Williams
4,983,160 A	1/1991	Steppe et al.
5,071,413 A	12/1991	Uitterberg
5,098,407 A *	3/1992	Okamura 604/248
5,100,394 A	3/1992	Dudar et al.
5,112,318 A *	5/1992	Novacek et al. 604/240
5,114,400 A	5/1992	Lynn
5,135,489 A	8/1992	Jepson et al.
5,149,327 A	9/1992	Oshiyama
5,199,948 A	4/1993	McPhee

FIG. 1 is a perspective view of an embodiment of our new, original and ornamental design;

FIG. 2 is a front elevational view thereof, the rear elevational view being a mirror image thereof;

FIG. 3 is a right side elevational view thereof, the left side elevational view being a mirror image thereof;

FIG. 4 is a bottom plan view thereof; and,

FIG. 5 is a top plan view thereof.

The structure shown in phantom is for illustrative purposes only and forms no part of the claimed design.
